ABSTRACT: The invention involves a method of operating a hydraulic actuated derrick or crane while lifting or pulling anchored objects by winching with the boom resting on a stiff leg and the derrick control in the boom down position. A pressure relief valve and bypass line is provided in the hydraulic circuit to function in lieu of and in conjunction with possible downward movement of the boom thus avoiding damage to the derrick or boom.

METHOD AND SYSTEM FOR AVOIDING DAMAGE TO DERRICKS BY PREVENTING OVERLOAD CONDITIONS

The present invention relates to a method of utilizing a derrick or crank boom mounted on a motor vehicle, which derrick or crane is hydraulically actuated for lift and lowering, and which is also provided with an independently operated winch and cable. More particularly, the invention also relates to an improvement in the hydraulic circuitry and associated apparatus for bypassing hydraulic fluid when the pressure condition reaches a preselected pressure short of that which would cause damage to the crane boom or derrick if not relieved. The improved system is particularly advantageous in preventing damage to the derrick or crane boom held in a near horizontal position while the associated winch is effecting a pulling operation such as withdrawing partially or substantially buried objects from the ground, or for pulling cable through conduit, for example.

Derricks of this type are highly mobile, usually mounted on auto truck bodies, and are equipped with a winch. The winch in many instances is mounted at the outer end of the boom. In other models of derrick or crane, the winch may be on the main boom column or in the bed of the truck. In these cases, the winch line or cable is threaded through a sheave at the outer end of the boom. The winches, regardless of position relative to the boom, generally have approximately the same line or cable pulling force. The line pulling force is independent of the angle of elevation of the derrick boom. The physical capacity of the derrick or crane boom to hold its position under load, however, varies at different angles of elevation from the horizontal. This is, of course, due to the increasing bending moment on the derrick boom as the derrick boom is lowered and/or extended from a near vertical position to the horizontal position. In unearthing objects, such as poles or stumps, for instance, one is faced with unknown forces of resistance due to soil condition, shape of pole, depth to which the pole is set, or, in the case of stumps, root and soil conditions and the like. Pulling cable through conduit is another example of unknown forces of resistance to which a derrick and winch might be applied. Heretofore, if the operator had his choice, he would park and set his truck so that the boom end could be positioned in close proximity to the object to be worked on, while yet at a maximum elevation to the horizontal. More often, however, the derrick must be located and set on the nearest level and firm surface, frequently on the road, and the boom extended toward the object to be moved, often times at an angle near to the horizontal.

Generally, the elevation of the crane boom or A frame derrick is controlled by a closed hydraulic fluid circuit and a double acting lift cylinder or cylinders. Such hydraulic lift cylinders operate with fluid on both sides of the piston. When fluid is forced into the cylinder below the piston, the piston travels away from the direction in which the pressure is exerted upon it, while the fluid above the piston is driven back into the fluid reservoir. On the other hand, when fluid is forced into the cylinder above the piston, the piston is forced down and the fluid below is forced out of the cylinder back to the reservoir. When the directional control or operating valve is in neutral position, all ports are closed and the piston is locked in place by fluid entrapped on both sides of the piston. It is in this neutral position that the boom elevation has been heretofore maintained as the winch is operated to apply its pulling force in tension between the object to be moved and the end of the boom.

To avoid bending damage to the derrick or crane, particularly so in the case of a boom having an extension or "stinger," ground props or stiff legs are employed to prop the derrick or boom close to the sheave over which the cable is in tension. This has not always prevented damage to the derrick when overloads occurred, as the boom lift cylinders continue to hold the load even though the stiff leg bends or may be depressed into the ground. The overload forces are then transmitted into bending moment on the derrick or boom as the end of the boom attempts to follow the load and bends, the lift cylinders being locked in neutral position.

Applicant has overcome the foregoing deficiencies in present hydraulic circuits for cranes and derricks of the rotating or A frame type by providing a protection arrangement in the hydraulic system. The method provides winching while the derrick or boom is in the boom down position against a stiff leg or ground support. For instance, in a pole-pulling operation, a constant moderate down pressure is maintained on the ground prop or stiff leg by the double acting lift cylinders of the boom. This is accomplished by incorporating a spring loaded pressure relief valve in the line or lines between the boom down side of the directional control valve and the top side of the boom lift cylinder or cylinders together with a bypass line from the pressure relief valve to the reservoir. The operator then secures the operating valve in the boom down position. The winch is engaged to place force in tension on the pole or object to be withdrawn. If these combined forces on the stiff leg or ground prop cause it to bend or sink into the ground, the boom will automatically follow it down, avoiding an overload bending moment from being applied to the boom, thus saving it from damage. Location of the spring-loaded relief valve and bypass in the hydraulic circuit is such that the hydraulic derrick's capacity to lift and hold loads is not affected as the spring loaded relief valve is adapted to operate only on the boom down pressure to assure that only moderate down pressure is applied.

It is accordingly the principal object of this invention to provide in the hydraulic circuit of a hydraulically actuated derrick or crane, bypass means adapted and arranged to effect a safety against excessive bending moment on the boom operative on the down pressure side of the hydraulic circuit controlling the lowering of the boom.

It is another object of this invention to accomplish pulling or winching operations while the crane or derrick is in the boom down position and applying moderate down pressure against a stiff leg or ground prop.

These and other objects and advantages will appear as the ensuing description proceeds, taken in conjunction with the accompanying drawings; in which:

FIG. 1 is an elevational view illustrating a derrick or crane having a boom mounted in a truck body, the boom having at its distal end a power winch, the cable of which is engaged adjacent the base of a pole set in the ground. In the instance illustrated, the crane is of the rotating type having an extendable boom;

FIG. 2 is a partial view of the elevation cylinder of the boom of FIG. 1, partly in section, together with the schematic hydraulic circuit for its operation in accordance with the present invention; and

FIG. 3 is a plan view of a conventional adjustable spring loaded pressure relief valve utilized in connection with a bypass line as a safety device in the invention described herein.

Referring in greater detail to the drawings, numeral 10 denotes a motor vehicle, the body of which has been provided with extendable legs or outriggers 11 and 12, to maintain the truck body stable. Mounted in the truck body is a derrick base 15. Above the base 15, in a rotating derrick as distinguished from an A frame derrick, is mounted a turntable 16, adapted for rotation with respect to the base 15, preferably on ball bearings. To the turntable 16 is mounted a frame 17, forming a clevis frame within which the end of the derrick boom 18 is pivotally mounted by a suitable shaft 19, preferably having self-aligning ball bearing bushings.

Also mounted to the clevis frame 17 between the frame and the derrick boom 18 is hydraulic boom lift cylinder 20. The boom lift cylinder 20, provided with a piston 22 and piston rod 22a, is pivotally mounted at one end to the frame at 21, and at the other end to the boom at 23. The pivots 19, 21 and 23, together with the extensible hydraulic lift cylinder and piston, provide triangulation, so that the boom 18 can be raised or lowered through a wide range of angles from about 15° from the vertical to about 15° below horizontal.

It will be understood that, although not illustrated, for maximum safety and stability the boom 18 is usually provided with a dual set of hydraulic lift cylinders and pistons oppositely mounted between clevis frame 17 and the derrick boom 18.

The boom 18 may also have a telescoping extension 25 which slides within the boom base 18 on suitable roller bearings and may also be provided with a hydraulically actuated digging auger 26. The boom extension or "stinger" 25 is operated in well-known manner by a hydraulic cylinder not shown. In the case of the A frame derrick, rotatability is not provided, but a boom extension may be provided.

At the outer end 27 of the boom (extension 25) is mounted a conventional hydraulic winch, driven by a hydraulic motor not shown, all well known in the art. Extending from the winch drum 28 mounted within the boom end 27, is a cable 29 secured to a pole 30 by a hook 31 engaged with a chain 32 secured around the pole near the ground.

A ground support or stiff leg 33 is shown extending between its ground shoe 34 and the boom end 27.

Turning to the hydraulic circuit for controlling the elevation capabilities of the derrick, wherein lies the safety feature of the invention, FIG. 2 shows schematically the lift cylinder 20 and associated hydraulic circuit. It is assumed that the circuit has been filled with hydraulic fluid and bled of air, all lines are full, the pump primed and operating.

Pump 35, usually driven by a power takeoff from the engine of the truck on which the derrick is mounted, pumps hydraulic fluid continuously from reservoir or tank 36 through lines 37 and 38 to an operational or distribution valve 39. The directional valve 39 is of conventional type having three distributive positions. It is preferably a spool-type valve having an operating lever 39a for hand operation to several different positions. When the lever 39a is placed in the boom lift position, the directional control operational valve passes fluid through lines 38 and 40, while permitting fluid to return through line 43, valve 44, lines 45 and 46, to the reservoir 36. When the lever 39a is placed in the boom down position, the fluid is passed through lines 38, 45 and 43, to the distal side of the piston 22, while returns via line 40, valve 39, and line 46 to the reservoir. The third principal position of the directional control valve 39 is its neutral position. When the lever 39a is in this position, both the lift and down positions of valve 39 are closed. In this position no work is done and fluid is merely circulated by the pump 35 through the valve 39, lines 37, 38 and 46 to and from the reservoir 36.

Assuming the directional control valve 39 is in its lift position, fluid will flow from the tank 36, line 37, into pump 35, then through line 38, distribution valve 39, line 40, into the cylinder 20, via connection 41 behind piston 22, forcing piston 22 connected to boom 18 upwardly. The piston 22, in turn, expels fluid in cylinder 20 ahead of piston 22 through connection 42 and line 43 to valve 44. Ports 44a and 44b of valve 44 normally function as a through return via line 45 to the fluid reservoir 36. The valve 44 is also provided internally with a spring-loaded poppet which when open passes fluid through port 44c to which bypass line 47 is connected, and returns hydraulic fluid to the reservoir 36.

Thus, when the derrick boom has been raised to any given elevation, the boom may be locked in place by lever 39a, placing operational valve 39 in its neutral position, so that the piston 22 remains stationary with fluid pressure in cylinder 20 on each side being equal, while the pump 35 continues to circulate oil from and to the reservoir 36 through lines 37, 38 and 46.

Let us assume now that the derrick boom has been extended and is being moved downwardly to the position shown in FIG. 1, viz, approximately horizontal. The pump 35 draws fluid from reservoir 36 through line 37, then through line 38 to valve 39, which is in its down position, causing fluid to be directed through line 45, through port 44a of the pressure relief valve 44, its through port 44b, line 43, connection 42, to

the distal side of the piston 22, thus forcing the piston 22 inwardly to lower the boom 18, placing a modest down pressure on the stiff leg 33. As previously mentioned, the valve 44 has a relief port 44c, normally closed by stemmed valve member, not shown, urged to its closed position by a spring bias. The tension of the spring may be adjustable, and preferably tensioned to open at about 1100 p.s.i.g. During the lowering of boom 18, hydraulic fluid behind the piston 22 is returned through connection 41, line 40, valve 39, line 38 and pump 35 to the reservoir 36. A suitable commercially available relief valve for this purpose is the Pneu-Trol Series RV-700. The operational valve 39 is then locked in the boom down position. As the stiff leg 33 resists the downward movement of the boom 18, the hydraulic pressure builds in excess of the tension of spring in pressure relief valve 44, permitting hydraulic fluid to be bypassed through line 47 to the reservoir 36. The winch 28 is started, exerting tension on the base of pole 30 against and equal and opposite force in compression exerted on the boom end 27 via the ground and stiff leg 33. Should the winch force in tension exceed the ability of the stiff leg and/or the ground to support the compression force developed, and either gives way, boom 18 will follow the stiff leg down as it or the ground gives way. This allows the operator time to halt the operation by slackening off the winch without the boom extension having been bent by excess bending moment.

The operation can again be commenced when the ground support has been replaced or repositioned, or if beyond the capacity of the equipment, heavier duty equipment can be brought to bear.

Directional control and relief valves used in the system above described are conventional and may be obtained commercially from a number of suppliers, such as Auto-Ponents, Deltrol Corporation, Bellwood, Illinois; Gresen Manufacturing Company, Minneapolis, Minnesota; or Waterman Hydraulics Corporation, Skokie, Illinois.

Having described the invention in detail, it will be apparent to those skilled in the art that other means may be provided to provide overload relief to prevent bending of the derrick boom upon overload, and all such means as fall within the spirit of the invention are intended to come within the scope of the appended claims, wherein there is claimed:

I claim:

1. In a method of pulling objects against frictional forces resisting the pulling thereof by winch, the cable of which extends from the distal end of a derrick or crane boom without damage thereto, the latter having hydraulic circuit means including a directional control valve for controlling lift and lowering thereof, the steps of which include securing the free end of the winch cable to the object to be pulled, lowering the derrick or boom to the appropriate angle to the horizontal, and supporting the derrick or boom by placing a stiff leg or ground support between it and the ground, the improvement comprising providing in the boom down portion of said hydraulic circuit a valve means adapted and arranged to bypass hydraulic fluid at a preselected pressure less than that pressure which will overload the derrick or boom had its position been locked by the directional control valve, maintaining said preselected pressure on the stiff leg by setting the directional control valve of the derrick or crane boom into boom down position, and operating the winch to exert pulling force on the object to be withdrawn, whereby in the event the winch pulling force is resisted by the object being pulled to the extent that the ground or ground support gives way, the boom follows the winch line load down without damage to the crane boom or derrick, and provides the operator time to disengage the winch and reposition the derrick or boom and stiff leg.

2. Method as claimed in claim 1, in which the bypass means includes a pressure relief valve having a port set to open at said preselected pressure and a bypass line to pass the fluid from said port to the system reservoir for recirculation so long as said port of the pressure relief valve remains open.
